(57) **CLAIM**

The ornamental design for a twist lock wall plate, as shown and described.

DESCRIPTION

FIG. 1 is a perspective view of a twist lock wall plate showing my new design;

FIG. 2 is a front view of the twist lock wall plate of FIG. 1;

FIG. 3 is a back view of the twist lock plate of FIG. 1;

FIG. 4 is a right side view of the twist lock plate of FIG. 1, the left side view of the twist lock wall plate of FIG. 1 being a mirror image of the right side view; and,

FIG. 5 is top view of the twist lock wall plate of FIG. 1, the bottom view of the twist lock wall plate of FIG. 1 being a mirror image of the top view.

The broken lines form no part of the claimed design. It should be understood that the claimed design extends to the broken line boundary but does not include the boundary.
